UNITED STATES PATENT OFFICE.

FRANCIS W. BRADY, OF ENGLEWOOD, NEW JERSEY.

FUEL-FEEDING MECHANISM FOR INTERNAL-COMBUSTION ENGINES.

No. 878,934.

Specification of Letters Patent.

Patented Feb. 11, 1908.

Application filed April 14, 1906. Serial No. 311,766.

To all whom it may concern:

Be it known that I, FRANCIS W. BRADY, a citizen of the United States, residing at Englewood, county of Bergen, State of New Jersey, have invented certain new and useful Improvements in Fuel-Feeding Mechanism for Internal-Combustion Engines; and I do hereby declare the following to be a full, clear, and exact description of the invention, 10 such as will enable others skilled in the art to which it appertains to make and use the same.

The object of my invention is to provide means for positively and periodically feeding 15 a hydrocarbon oil to a vaporizer in such a way that the oil feed is abruptly begun and ended at the proper times and after-drip is prevented.

My improvements are particularly applicable to, and are herein described in connection with an internal combustion engine in which the oil is periodically fed to a vaporizer in the path of the air entering the combustion chamber and in which the period of oil 25 feed continues during part only of the suction stroke. Their utility is not, however, limited to such engines.

Referring to the drawings, Figure 1 is a side elevation of the engine cylinder, showing the 30 mechanism for actuating the rock shaft which operates the valve mechanism and a portion of the mechanism for feeding the fuel. Fig. 2 is a front elevation, partly in section, of the same showing the oil feed valve 35 partly open. From both of these figures the inlet and exhaust mechanisms have been omitted. Fig. 3 is a cross-section on a larger scale showing the oil feed mechanism. Fig. 4 is a cross section on the line 4—4 of Fig. 3. Fig. 5 is a detail sectional view of the sleeve 40 b'; Fig. 6 is a cross-section on the line 6—6 of Fig. 5, and Fig. 7 is a section on line 7—7 of Fig. 2 showing the inlet and exhaust valve mechanisms.

45 The same reference numerals are applied to like parts throughout.

The cylindrical casing a containing the combustion chamber may be of any desirable construction, and should be provided with an 50 appropriate water-jacket. The base of the cylinder carries a bracket b, in which is journaled a cam shaft c, adapted to be driven from the crank shaft of the engine by reducing gearing (not shown) of such character 55 that the cam shaft is rotated once for every two revolutions of the crank shaft. The cam

shaft carries a cam d, which engages with a roller e on the end of an arm f pivoted in a bracket g, which is also attached to the base of the cylinder. A rod h, connects the other end of the arm f to which it is pivotally attached, with a laterally extending arm i on a rock shaft j. The rod h is also pivoted to the outer end of the arm i. The rock shaft j is journaled in upwardly extending brackets k bolted to the casing a, and carries a sleeve l rigidly attached to it. This sleeve l carries a forked arm m. The fork at the outer end of the arm m embraces a flanged collar n which is placed on the reduced upper end of the valve stem o and clamped in place by a nut p. The stem o extends vertically through a tubular opening in the head of the cylinder and carries at its lower end a bell shaped valve r adapted to be seated by an upward movement of the rock shaft on an appropriate seat between the combustion chamber of the engine and the valve chamber s in the head of the cylinder. Surrounding the stem o and fitting snugly in the tubular opening in the head of the cylinder is a sleeve t screw-threaded at its upper end and having a reduced portion terminating in a beveled shoulder u.

Above the beveled shoulder and between 85 the inner walls of the tubular opening and the reduced portion of the sleeve t appropriate packing material is inserted and over the sleeve t a collar v resting on the top of the tubular opening and having a beveled lower end is slipped and pressed into place by the nut w screwed onto the upper end of the sleeve t. The lower end of the sleeve t is provided with a cylindrical recessed portion 90 screw-threaded, as shown, into which a sleeve x is adapted to be screwed and firmly secured in place by a set screw y passing through the sleeve t. The sleeve x has an 95 enlargement at its lower end provided with a beveled shoulder, and from the outer surface of this beveled shoulder downwardly directed ducts z are bored inwardly into communication with a cylindrical recess a' forming a distribution chamber on the interior of the sleeve x. Grooves m' are cut in 105 the stem in such position as to establish communication between the distribution chamber and the space just above the surface of the valve r when that valve is open. At the lower end of each groove is a sharp 110 shoulder (see Fig. 3) adapted to throw the oil out onto the valve surface. Excepting

at this recessed portion the interior of the sleeve x fits snugly onto the stem o , but the sleeve x is of such diameter as to leave a chamber between its outer surface and the inner walls of the opening through the cylinder head. In this chamber and sliding on the sleeve x is a collar b' which is pressed downward by compression spring c' between it and the lower end of the sleeve t .
 10 This collar b' (Fig. 5) is provided with a recessed portion forming an oil chamber and communicating with the oil duct d' and oil supply pipe e' . The lower end of this collar b' has a bevel corresponding with the beveled shoulder on the lower end of the sleeve x .
 15 The portion of the collar b' above the recessed portion fits snugly the interior of the tubular opening in the cylinder head, and is provided with a series of grooves f' arranged around its circumference to permit the passage of air as the collar b' is reciprocated on the sleeve x .

The portion of the collar below the recess is of reduced diameter so as to form a chamber between it and the tubular opening.
 20 The opening through the cylinder head is enlarged at its lower end and screw-threaded on its interior surface to receive a cap g' which embraces and helps to hold in place the sleeve x and closes the lower end of the chamber between sleeve x , and the interior surface of the opening through the cylinder head. The valve stem o is provided with grooves or ducts which lead the oil from the 25 distribution chamber a' to the surface of the valve r . Extending laterally through the cylinder head is a rod h' cut away at its inner end to form a shoulder i' , and this shoulder i' is adapted to engage with the upper 30 edge of the recessed portion of the collar b' . This rod h' is reduced at its outer end which passes through and is held in place by the screw-bolt j' provided with the lock-nut k' . Rigidly secured to the arm h' outside of the 35 cylinder head is an arm l' one end of which is connected to the casing a by a spring m' and the other end of which projects into the path of a screw-pin n' secured in a collar o' on the rod h . The rod h' is also provided 40 with an adjustable stop comprising an arm p' rigidly secured to the rod and a screw-pin r' extending through said arm into engagement with the top of the casing a .

The operation of this device is as follows:—
 45 The spring m' and the screwpin p' normally hold the rod h' in the position shown in Figs. 1 and 3, and the shoulder on the inner end of the rod h' in a horizontal position, in which position the spring c' forces the collar b' down into engagement with the beveled shoulder on the sleeve x . In the position of parts shown in Fig. 1, the cam d has raised the outer end of the arm f and thereby rotated the rock shaft j and depressed the arm o to 50 open the valve r . At this position the en-

gine is in about the middle of its exhaust stroke and the products of combustion are being forced past the valve r and out through the exhaust port B in the valve chamber s by the in-stroke of the piston. 70 During this in-stroke and the following out-stroke the cam continues to hold the valve r open. The suction caused by the out-stroke of the piston closes the exhaust port B and opens the air inlet port A in the chamber s , 75 drawing air into this chamber, across the face of the valve r and into the combustion chamber of the engine. At a predetermined point, after the commencement of this out-stroke the pin n' strikes the end of the arm l' 80 and rocks the rod h' against the action of the spring m' . This rocking of the rod h' causes the shoulder on the end of that rod to lift the collar b' against the action of the spring c' and oil flows between the outer surface of the 85 collar b' and the inner surface of the tubular opening through the ducts z into the recess a' and through the grooves in the valve stem o onto the face of the valve r . This rocking of the rod h' by the pin n' is secured at the 90 proper moment by means of the sharp projection on the cam d . At approximately the end of the out-stroke of the piston, this sharp projection rides from under the roller e on the end of the arm f and arm i on the rock 95 shaft j is raised, seating the valve r but owing to the construction of the parts the oil feed is stopped by the disengagement of the pin n' with the arm l' before the closing of the valve r , thus allowing the air to continue to 100 sweep over the face of this valve after the oil feed has stopped. This interval of time may be regulated by screwing in and out the pin n' . After the closure of the valve r at the 105 end of the out-stroke, the next in-stroke of the piston begins, and compresses the gases in the combustion chamber. At approximately the end of the in-stroke ignition is secured in any appropriate way and the piston is forced outwardly, the valve r remaining 110 closed. At the beginning of the next in-stroke the valve r is opened by the cam d , thus completing the cycle of operations.

It will be seen that with this construction of the oil feed mechanism when the pin n' is 115 lifted from the arm l' and the rod h' is rocked by the spring m' into the position shown in Fig. 1, the collar b' is abruptly seated by the spring c' on the beveled shoulder of the sleeve x , thereby forcibly expelling the oil which has accumulated between these surfaces and suddenly stopping the flow of oil. In other words, the collar b' acts as a plunger in the oil chamber above the ducts z and at the conclusion of the oil feed it forcibly expels the oil in the chamber and abruptly cuts off the oil feed in close proximity to valve stem o , thus preventing after-drip. The pressure on the oil is preferably maintained at all times at a point where the oil is forced 120 125 130

in flat jets through the ducts *z* against the stem whenever the ducts are open. By the construction shown this pressure acts against the collar *b* to hold it firmly closed. The pressure may be obtained by elevating the oil tank *C* as shown or in any other suitable way.

The nature of my improvements will be understood from this description of the form 10 in which I prefer to embody them, though it is obvious that the improvements may be embodied in other forms without departing from the spirit of my invention.

What I claim is:-

15 1. In an internal combustion engine, a valve having a vaporizing surface, a stem on said valve, an oil chamber surrounding said stem, a partition between the chamber and the stem, a plurality of ducts through said 20 partition and spaced about said stem, and a valve in the oil chamber controlling said ducts, whereby when the valve is open oil flows from the chamber through the ducts and down the stem onto the vaporizing 25 surface.

2. In an internal combustion engine, a valve having a vaporizing surface, a stem on said valve, a series of ports about said stem, a distribution chamber communicating with 30 said ports, an oil chamber, an eduction port in said chamber, an oil duct leading from said port to the distribution chamber, a plunger in the oil chamber adapted to close the eduction port, means for withdrawing the plunger 35 to open the port, and means for feeding oil into the chamber between the plunger and the eduction port when the plunger is withdrawn.

3. In an internal combustion engine, a 40 valve having a vaporizing surface, a stem on said valve, a series of ports about said stem, a distribution chamber communicating with said ports, an oil chamber, an eduction port in said chamber, an oil duct leading from said 45 port to the distribution chamber, means for feeding oil through the oil chamber while the eduction port is open, and means for abruptly forcing the oil in the chamber through the eduction port and closing said port to shut 50 off the oil feed.

4. In an internal combustion engine a valve having a vaporizing surface, a stem on said valve, an oil chamber surrounding said stem, a partition between the chamber and the stem, a plurality of ducts through said 55 partition and spaced about said stem, a plunger in the oil chamber adapted to close the ducts, a spring for moving the plunger into a position to close the ducts, a cam for lifting the plunger against the action of the spring, and means for operating said cam.

5. In an internal combustion engine, a valve having a vaporizing surface, a stem on said valve, ports about said stem, a distribution chamber communicating with said ports,

an oil chamber communicating with the distribution chamber, means for supplying oil to said oil chamber under pressure, a plunger in said oil chamber, means for raising said plunger to open communication between the oil and distribution chambers against the pressure of the oil, and means for depressing the plunger to force the oil in the oil chamber onto the surface of the valve and close the communication between the oil and distribution chambers.

6. In an internal combustion engine, a valve, a stem on said valve, a sleeve surrounding said stem and having an enlarged end with a beveled surface, a casing secured to the enlarged end of the sleeve, whereby a chamber is formed between the sleeve and casing, a collar surrounding said sleeve between the sleeve and casing and having a beveled end adapted to fit the beveled surface of the sleeve, a spring for pressing the end of the collar against said surface, a cam engaging with the collar, means for rocking the cam to lift the collar against the action of the spring, oil ducts through the beveled surface on the sleeve leading to the valve stem and means for feeding oil into the chamber between the sleeve and casing.

7. In an internal combustion engine, a valve, a stem on said valve, a sleeve surrounding said stem, a casing surrounding said sleeve, an oil chamber between the sleeve and casing, means for feeding oil to the oil chamber, an oil passage from the oil chamber to the valve surface, and a valve in the oil chamber for controlling said passage.

8. In an internal combustion engine, a valve, a stem on said valve, a sleeve surrounding said stem, a casing surrounding said sleeve, an oil chamber between the sleeve and casing, means for feeding oil to said chamber, an oil passage from the chamber to the valve surface, a collar surrounding the sleeve and movable thereon in said chamber, and means for reciprocating said collar to open and close the oil passage.

9. In an internal combustion engine, a valve, a stem on said valve, a sleeve surrounding said stem, a casing surrounding said sleeve, an oil chamber between the sleeve and casing, means for feeding oil to said chamber, an oil passage from the chamber to the valve surface, a collar surrounding the sleeve and movable thereon in said chamber, and means for reciprocating said collar to open and close the oil passage, said means comprising a shaft, a cam on said shaft engaging with the collar and means for rocking said shaft.

10. In an internal combustion engine, a valve, a stem on said valve, a sleeve surrounding said stem, a casing surrounding said sleeve, an oil chamber between the sleeve and casing, means for feeding oil to said chamber, an oil passage from the chamber,

- ber to the valve surface, a collar surrounding the sleeve and movable thereon in said chamber, a spring acting on said collar to hold it in a position to close the oil passage, a shaft, 5 a cam carried by said shaft and engaging said collar, means for moving the valve stem to open the valve, and means for turning the cam shaft to lift the collar against the action of the spring and open the oil passage, while 10 the valve is open.
11. In an internal combustion engine, a valve, a stem on said valve, a sleeve surrounding said stem, a casing surrounding said sleeve, an oil chamber between the 15 sleeve and casing, means for feeding oil to said chamber, an oil passage from the chamber to the valve surface, a collar surrounding the sleeve and movable thereon in said chamber, a spring acting on said collar to hold it in a position to close the oil passage, a shaft, 20 a cam carried by said shaft and engaging said collar, a rocker to which the valve stem is connected, a rod connected to the rocker, means for moving the rod to actuate the rocker, a rock arm carried by the cam shaft, 25 and a stop on the rod adapted to engage the rock arm to turn the cam shaft and lift the collar against the action of the spring.
12. In an internal combustion engine a valve having a vaporizing surface across 30 which the air entering the combustion chamber passes, a stem on said valve, an oil chamber, a series of ducts leading from the oil chamber to the stem and arranged about said stem, a series of ducts in said stem, means 35 for feeding oil through the first mentioned ducts and down the ducts in the stem, and means for deflecting the oil from the ducts in the stem onto the valve surface.

In testimony whereof I affix my signature in presence of two witnesses.

FRANCIS W. BRADY.
